UNITED STATES PATENT OFFICE

129,368

DESIGN FOR A COMBINATION PENCIL AND POCKETKNIFE

Patrick J. Cummings, Attleboro, Mass.

Application March 13, 1941, Serial No. 99,558

Term of patent 3½ years

To all whom it may concern:

Be it known that Patrick J. Cummings, a citizen of the United States, residing at Attleboro, in the county of Bristol and Commonwealth of Massachusetts, has invented a new, original, and ornamental Design for a Combination Pencil and Pocketknife, of which the following is a specification, reference being had to the accompanying drawing, forming a part thereof.

Fig. 1 is a side elevational view of a combination pencil and pocketknife, showing my new design.

Fig. 2 is a plan view thereof.

I claim:

The ornamental design for a combination pencil and pocketknife, substantially as shown.

PATRICK J. CUMMINGS.
